UNITED STATES PATENT OFFICE.

JOHN G. SCHOFIELD, OF WASHINGTON, DISTRICT OF COLUMBIA.

DISPENSING DEVICE.

Application filed January 10, 1928. Serial No. 245,882.

This invention relates to a dispensing device, and more particularly one adapted for attachment to a tube from which the content is extruded by manually collapsing the tube, 5 such as the tubes commonly employed for vending tooth paste, shaving creams, etc., or other plastic or semi-liquid material.

One of the chief objections to such tubes in common use, closed by a screw cap, is that 10 the users frequently fail to replace the cap after using a portion of the contents, thereby permitting the tooth paste, for instance, to become hardened at the end of the tube nipple, with the undesirable result that when 15 the tube is next used, pressure upon it expels too much of the material, and too suddenly, resulting in waste and other inconveniences.

Furthermore, the usual way of extruding 20 the contents of these tubes is wasteful, as there is no fixed way of regulating the amount of content expelled at any one time. I aim to entirely obviate the foregoing objections, which I believe I do by providing 25 a device readily adjustable to and removable from the nipple of an ordinary tube, or those in universal use, that will, in effect, keep the nipple "always closed", so far as the main bulk of the contents is concerned, but at the 30 same time, through a very simple manipulation of the device, deliver just the required amount of material and present it at a point, and in a manner to be conveniently removed with a tooth brush, shaving brush, or the 35 like, leaving as intimated, the nipple closed so as not to waste or harden the remaining material.

With slight modifications as to fit of the moving part of the dispenser, a more liquid 40 content may be dispensed, as for instance in cases where just a certain amount of the contents is prescribed.

In the drawings illustrating the invention—

45 Figure 1 is a perspective view of the dispenser closed;

Figure 2 is a similar view, with the parts in delivery position;

50 Figure 3 is a transverse central section, the pocket or trough of the core being in position to receive a charge of material from the nipple of the tube;

Figure 4 is a top plan view.

55 Referring to the drawings, the numeral 1 designates a collapsible tube, such as is commonly used for vending tooth paste, shav-

ing cream, etc., and 2, the usual externally threaded nipple thereof. The numeral 3 designates the dispenser as a whole. It comprises an internally threaded short 60 sleeve 4 which merges into a slightly elongated cylindrical casing 5 closed at its ends with the exception of oppositely positioned V-shaped recesses 6, which form the open ends of delivery opening 6'. Within the 65 casing and fitting snugly, is a rockable core 7 in which there is a trough-like pocket 8 extending for the entire length of the core, the pocket being adapted to be brought into registry with the recesses 6 in the delivery 70 opening 6' in the casing, for the purpose of delivering a portion of the contents of the material holder or tube, and opposite the opening in the nipple of the holder to receive a charge of the material. The casing 75 is recessed circumferentially at one side, and in the middle thereof, as indicated at 9, the circular recess being adapted to receive the shank of a headed pin 10 secured in the core and by which the core is manually manipulated in its rocking movement. The depth of the recess 9 is such that the pocket may be alternately moved from one extreme position to the other, which final positions are those in which the core receives a charge of 80 material in one instance and delivers it in another.

The edges of the recesses 6 register accurately with the open ends of the trough-like pocket, so that when the core is in position 90 to deliver the material, there is in effect, a continuous trough or groove extending throughout the length of the casing and core, so that a tooth brush for instance, can be passed through the trough to conveniently 95 remove the contents thereof. As soon as the material is removed, the core is rocked to the position shown in Figure 3 when it is opposite the opening in the nipple and in position to receive another charge, when the 100 tube is pressed.

From the foregoing, it will be seen that at no time is the main body of the contents exposed to the air. In other words, the core forms a complete closure for the tube or 105 holder in all positions.

In dispensing the contents of a collapsible tube the tube will be pressed slightly, forcing a part of the contents into a pocket 8, the core is then rocked, delivering this much 110 to the delivery opening and after it has been removed by a tooth brush or otherwise, the

core is rocked back to position to bring the pocket opposite the opening in the nipple, when the tube will be again slightly pressed, filling the pocket for future delivery. However, it has been found in practice that this is virtually automatically and unconsciously done by a user.

I claim:

1. A dispensing device comprising means for attachment to the open end of the nipple of a collapsible tube, a casing having oppositely disposed recesses in its ends, and an opening above the means for attachment to the tube, a core rockably held in the casing, and having a trough-like pocket open at both ends, the ends being adapted to be brought into registry with the recesses in the ends of the casing, so as to form a continuous trough therethrough, for the purpose described, the core being adapted to be rocked to position to receive a charge of the material from the tube when in one position, and deliver the same through the casing when rocked in the opposite direction, and means for limiting the movement of the core in both directions.
2. In a dispensing device, in combination, a casing having oppositely disposed recesses in its ends, and an outlet opening, a core rockably held in the casing and having a troughlike pocket open at both ends, the ends being adapted to be brought into registry with the recesses in the face of the cas-

ing, so as to form a continuous trough therethrough, the core being adapted to be rocked to position to receive a charge of the material to be delivered when in one position, and to deliver the same through the casing when rocked in the opposite direction, and means for limiting the movement of the core in both directions.

35

40

3. A dispensing device including a depending internally threaded sleeve adapted for attachment to the nipple of a holder, and a casing having oppositely disposed recesses in its ends, and secured to the sleeve, said casing being provided with a delivery opening and also having a circumferential recess at one side of said delivery opening, a rockable core held in the casing, and having a troughlike pocket open at both ends, the open ends of said core being adapted to be brought into registry with the recesses in the ends of the casing, so as to form a continuous trough therethrough, a pin carried by the core and serving both as means for facilitating the movement of the core in the casing and also as a stop for limiting the movement of the core in either direction, said pin being adapted to engage the upper edge of the casing when rocked in one direction, and to engage the bottom of said circumferential slot when rocked in the other direction.
